[57] CLAIM

The ornamental design for a lamp, as shown and described.

DESCRIPTION

FIG. 1 is a perspective view of a lamp showing my new design.

FIG. 2 is a top plan view of the lamp of FIG. 1.

FIG. 3 is a bottom plan view of the lamp of FIG. 1.
FIG. 4 is a sectional view of the lamp taken along line
4—4 of FIG. 2 the light bulb being shown in broken lines for illustrative purposes only.
All sides of the lamp are identical.
